Specification for Design.

Patented Apr. 10, 1917.

Application filed January 31, 1917. Serial No. 145,809. Term of patent 14 years.

To all whom it may concern:

Be it known that I, JERRY D. CLINE, a citizen of the United States, residing at Akron, in the county of Summit and State of Ohio, have invented a new, original, and ornamental Design for Non-Skid Treads, of which the following is a specification, reference being had to the accompanying drawing, forming a part thereof.

Figure 1 is a cross sectional perspective view of the non-skid tread, and

Fig. 2 is a fragmentary plan view of the non-skid tread.

I claim:

The ornamental design for a non-skid tread, as shown.

JERRY D. CLINE.
